Patented Apr. 30, 1918.

UNITED STATES PATENT OFFICE.

THEODOR R. WILLWERSCHEID, OF ST. PAUL, MINNESOTA.

SPRAY FINISHING-MACHINE.

1,264,358.

Specification of Letters Patent. Patented Apr. 30, 1918.

Application filed November 19, 1917. Serial No. 202,692.

To all whom it may concern:

Be it known that I, THEODORE R. WILLWERSCHEID, a citizen of the United States, residing in St. Paul, in the county of Ramsey and State of Minnesota, have invented new and useful Improvements in Spray Finishing-Machines, of which the following is a specification.

The ordinary method of applying finishing materials, such as paint, varnish, enamel, lacquer, etc., with the aid of compressed air consists in an operator manually directing a stream of sprayed fluid upon the products to be coated. Such method is slow and costly; the coating is frequently uneven; and the vapors resultant from such process are unhealthful and dangerous.

The object of my invention is to provide an economical, sanitary and labor-saving machine for applying such atomized finishing materials.

More specifically, it is my object to produce a machine of this class embodying mechanical feeding apparatus capable of highly efficient operation by unskilled labor, whereby a uniform coating of finishing material may be quickly and automatically applied to manufactured products. It is further my object to protect operators and plant by confining and expelling harmful vapors and gases arising from the sprayed finishing material, thereby eliminating danger of explosion, as well as providing more sanitary working conditions for employees.

In the accompanying drawings, Figure 1 is a longitudinal side elevation, partly in section, of my machine; Fig. 2 is a central transverse section on the line 2—2 of Fig 1; and Fig. 3 is an elevation taken from the feeding end of the machine.

Referring to the drawings, it will be seen that my machine consists primarily of a housing A, a conveyer B passing therethrough, paint spraying means C, and a fume removing conduit D for said housing.

The housing A comprises inclosing walls 10 having a top 11 thereon, and a door 12 in one of the walls to provide access to the interior of the housing.

Said conveyer B consists of an endless chain 13 composed of links 14 having flat ears 15 projecting laterally from the side of the chain and forming bearing surfaces 55 for objects 16 to be carried on the horizon-

tal section of the conveyer through the housing A, which is arranged midway of the chain. Both the upper and lower runs of said chain pass through said housing, openings 17 and 18 being formed in opposite walls of the housing to provide a passageway for the chain and objects thereon. Said chain passes over sprocket wheels 19 (only one shown) revolvably mounted in bearing supports 20 arranged at opposite sides of the housing A, and power is applied to either of said sprocket wheels to revolve the chain 13.

A sprayer 21 is suspended over the upper run of the conveyer B within the housing 70 by a bracket 22 secured to the wall 10, and said sprayer is supplied with finishing fluid and compressed air through the tubing 23 and pipe 24 respectively. Said tubing connects with a container or reservoir 25 for paint, varnish, or the like, elevated above the sprayer 21 and preferably placed on the exterior of the housing. The air pipe 24 transmits compressed air from an air compressor (not shown) to said sprayer 21, 75 and a branch air pipe 26 connects with said air pipe 24 and terminates on the exterior of the housing immediately above the incoming chain 13. A small orifice 27 is formed in the end of this pipe and a blast 80 of air is thus directed upon the objects 16 before their entrance to the housing A to remove dust and dirt therefrom.

A sheet-metal fume expelling conduit D is provided, which enters the housing 90 through the top 11 and is bifurcated to form diverging funnels 28 and 29 which terminate adjacent to the sprayer 21. An exhaust fan (not shown) creates suction within the conduit D and vapors arising 95 from the atomized finishing material are drawn through the funnels and discharged on the outside of the plant. A drip pan 30 occupies the lower part of the housing between the upper and lower runs of the conveyer B and receives any surplus of the jet 100 of finishing material which may not adhere to the object being coated. Beneath the upper run of said conveyer chain and on the outside of the housing, I provide tables 31 105 and 32 over which the conveyer chain 13 travels in entering and passing from the housing A, respectively, and the table 31 on the feeding end of the conveyer is further supplied with a vertical abutment or 110

flange 33 parallel to the chain 13. These tables 31 and 32 support the upper run of the chain 13 and prevent its dragging against the housing walls 10, while the abutment 33 facilitates the placing of objects 16 upon the conveyer. Trays 34 may, if desired, be placed beneath the lower run of the chain 13 to catch possible excess finishing material dropping from the conveyer B.

10 In use, suction is produced in the funnels 28 and 29 by means of an exhaust fan (not shown). Power is applied to one of the sprocket wheels 19 to drive the conveyer chain 13. The products of manufacture, 15 which are to be coated, are placed on the conveyer chain 13 as it passes over the table 31. The guard or abutment 33 prevents such products from slipping off the back side of the conveyer and thus enables the 20 operator to place objects on the chain with greater despatch. Such products are conveyed into the housing A and pass beneath the sprayer 21. Paint, varnish, or other finishing material, is fed to said sprayer 25 from the container 25 via the tubing 23 and compressed air is also supplied to the said sprayer 21 through the pipe 24 and operates to project a fan-shaped jet of atomized fluid downward and distribute the same evenly 30 over the objects on the conveyer. No specific type of sprayer 21 is claimed, as any of the commercially well-known types may be used. Compressed air also escapes through the orifice 27 in the pipe 26 and 35 blows dust and dirt from the objects 16 prior to their admission to the housing. After passing beneath the sprayer 21 and receiving a coating of finishing material, the objects pass out of the housing over the table 40 32 and an attendant removes them from the machine. The suction previously set up in the funnels 28 and 29 exhausts the fumes and vapors of turpentine, and other volatile elements of the finishing material, from the 45 housing and eliminates danger of explosions, as well as provides a healthful and sanitary atmosphere for the attendants.

I have illustrated the preferred embodiment of my device, but I do not limit myself 50 to the specific details of construction herein set forth, nor to any particular form of object to be coated, as it is obvious that various

modifications may be made therein without departing from the spirit of my invention.

Having described my invention, what I 55 claim as new and desire to protect by Letters Patent is:

1. In a machine of the class described, a closed housing, a spraying device therein, a conveyer passing through said housing 60 and adapted to convey objects beneath said spraying device, a loading table at one side of said housing over which said chain passes, an abutment on said table parallel to said chain, and an exhaust conduit for said 65 housing.

2. In a machine of the class described, a closed housing, an endless, horizontally-disposed conveyer chain passing through said housing, a spraying device in said housing 70 above said conveyer chain, and an exhaust conduit communicating with said housing, the end of said conduit being bifurcated and projecting within said housing to form diverging funnels lying upon each side of 75 said spraying device and terminating adjacent said conveyer chain.

3. In a machine of the class described, a stationary spraying device, a housing surrounding said spraying device, a door for 80 said housing, an endless, horizontal conveyer chain passing through said housing and beneath said spraying device, an air nozzle on the exterior of said housing above said conveyer chain, said air nozzle being adapted to blow dust from articles on said conveyer chain before their admittance to said housing, and means for exhausting volatile matter suspended in the air in said housing.

4. In a machine of the class described, a 90 housing having openings in the walls thereof, a power driven conveyer chain passing through said openings, sprocket wheels without said housing for said chain, supports for said sprocket wheels, supporting 95 tables for said chain at opposite sides of the housing, a spraying device within said housing, means to supply finishing material and compressed air to said spraying device, and a fume exhaust conduit for said 100 housing.

Whereof I have hereunto subscribed my name to this specification.

THEODOR R. WILLWERSCHEID.
